UNITED STATES PATENT OFFICE.

JOHN HUBER, OF BELLWOOD, PENNSYLVANIA.

SHEET-METAL-BENDING DIE.

Application filed September 26, 1922. Serial No. 590,617.

To all whom it may concern:

Be it known that I, JOHN HUBER, a citizen of the United States, residing at Bellwood, in the county of Blair and State of Pennsylvania, have invented certain new and useful Improvements in Sheet-Metal-Bending Dies, of which the following is a specification.

My invention relates to the art of bending sheet or plate metal between suitably formed dies. It has in view to utilize the main frame of a power actuated shear, punch, press or other similar machine, by providing suitable dies and supporting and adjusting mechanism, capable of attachment to such a machine, and adapted to operate in the manner hereinafter described.

The invention particularly refers to means for mounting and supporting the plate to be flanged, to an improved form of die mechanism, means for maintaining a temporary holding pressure on the plate during bending, and to various other features of the mechanism, as hereinafter more fully described. The present invention is a further development of that shown in my prior Letters Patent No. 1,482,927, dated February 5, 1924.

In the drawings:

Figure 1 is a partial view in side elevation of a standard punch, shear, or press, equipped with the necessary mechanism for flanging a circular boiler plate or head;

Fig. 2 is a cross sectional detail view on the line II—II of Fig. 1;

Fig. 3 is a detached partial view similar to Fig. 1, showing the pressing die in raised position at the commencement of the bending operation;

Fig. 4 is a diagrammatic detail view of the valve controlling mechanism for the fluid-actuated pressing cylinders;

Fig. 5 is a detail view showing one of the valve arms in its alternating position;

Fig. 6 is a detail plan view of the operative mechanism of Fig. 4;

Fig. 7 is a sectional detail view, enlarged, of the pressing mechanism for holding the plate during the bending operation;

Fig. 8 is a sectional plan view thereof on the line VIII—VIII of Fig. 7; and

Fig. 9 is a transverse sectional view on the line IX—IX of Fig. 8.

In the drawings, 2 is the main frame or housing of a standard punch, shear, or press, having the usual anvil block or base 3 and

head 4. Within the head 4 is usually mounted a cam or eccentric-actuated reciprocable head or base, to which is attached the punch or shear of common use. The actuating shaft *a* for such cam or eccentric is usually provided with a driven gear *b* engaged by pinion *c* of power shaft *d*, of well known construction, as in Fig. 4.

The usual punch or shear, in the present case, is replaced by a block 5, adapted to be raised and lowered by the actuating mechanism in connection with the customary clutch, for intermittent operation. Block 5 is provided with a centrally arranged temper screw 6, which is connected by its swivel head 7 and retaining plate 8, or in any other suitable manner, with the reciprocable die block 9.

The die block 9, in the present construction, is adapted for vertical movement and operation upon the practically horizontal blank, by vertical movement thereagainst. For such purpose, and to facilitate the easy bending and action of the die, its lower face 10 is slightly sloped backwardly from the front corner, and its front face 11 is sloped slightly forwardly of its front general vertical direction, said faces being joined by a rounded knuckle or corner 12.

The object of such formation is that the die block 9, in its downward movement against the projecting edge of the plate *e*, as in Fig. 3, will engage the outer edge of the plate by its slightly sloping face 10, bending it downwardly over the right angle corner of the L-shaped anvil block 14, which is mounted upon the forwardly and upwardly extending bracket support 13 of the machine. This latter feature is generally similar to the bracket construction shown in my prior application above referred to, and is adapted to be fitted upon and screwed to the shouldered base 3 of the machine, as will be readily understood.

In operation, the plate *e* having been located with its edge extending over anvil block 14 in range of the bending die, and with the clamping mechanism applied thereto, as hereinafter described, downward movement of die 9 easily and gradually bends the projecting portion of the plate down around and upon anvil 14, and against the inner face thereof, as in Fig. 1, at right angles to its upper face, resulting in a right angle flange. The operation is easy, gradual, and complete, due to the angular ar-

angement of the parts, and avoiding the necessity of subsequent or double flanging.

The circular plate *e* to be flanged is pivotally mounted at its center by a hole upon a centering pin or stud 17 extending upwardly from and supported by a block 18 which is slidably mounted upon a pair of supporting channel or other bars 19—19 incorporated with and extending outwardly 10 from the base 13, and resting at their outer ends upon a foundation support 20, as in Fig. 1.

The centering block 18 is slidably and adjustably mounted on channel members 19 and fixedly secured in its desired position when adjusted by set screws 21. Centering pin 17 is a portion of a larger stem or bolt 22 in threaded engagement with the hub or bearing 18, through which it extends, and 20 is provided with the terminal nut 23 for adjustment therein. It extends upwardly through such bearing and is provided with an adjusting nut 25, whereby to fixedly locate and hold the stem 22 exactly at the 25 right height for pivotal mounting of plate *e* on shouldered stud 17. A terminal nut 26 is used, if desired, to retain the plate loosely in rotative position.

For the purpose of preliminarily clamping the plate downwardly upon anvil 14, I 30 use a series of pressing shoes 27, 27, and 28. These are mounted by guiding studs 29 in the lower portion 30 of a downwardly extending adjustable frame 31, as clearly 35 shown in Figs. 7 and 9. The shoes are of sufficient width to engage an ample area of the plate to hold it firmly, and the shoes themselves are pressed downwardly by a plurality of wedges 32. Wedges 32 are 40 formed as portions of reciprocable bars 33, a pair of such bars being preferably utilized, each having a piston stem 34 connected with a plunger 35 of a fluid-actuated cylinder 36. Said cylinders are mounted at opposite ends 45 upon the projecting portions 30^a of the bottom plate 30, and bars 33 are mounted for longitudinal movement across and underneath an upper plate 37 of frame 31. By such construction, the simultaneous actuation of bars 33 move the several wedges 32, depressing the several studs 29, and pressing all of the shoes 27, 27, 28 downwardly 50 upon the portion of plate *e* which extends over the anvil block 14, and holding it firmly thereupon.

For the purpose of guiding shoes 27—28 and maintaining them in operative position at all times, each shoe is provided with upwardly extending guiding pins 38 projecting through suitable bearings in plate 30, having terminal washers 31^a and nuts. A spiral spring 33^a normally presses upwardly against the washer 31^a to retract the pressing shoe, which spring is preferably surrounded with a protecting shell 34^a, provid-

ing for ample range of movement. Its upper edge limits undue downward movement of the pin 38 and shoe by abutting engagement of washer 31^a. Such construction being provided at each side of wedge-actuated 70 studs 29 ensures equalization of the pressure and prompt retraction of the several shoes when the wedges are withdrawn.

For the purpose of automatically operating the pressing mechanism, I provide a controlling valve 24 to control pressure to one end of each of cylinders 36, simultaneously, by means of a fluid pressure supply pipe 40, having branches 41—41 connected with each cylinder, as shown. Valve 24 is provided with a normal pressure supply line 42 and a suitable exhaust, so that, as the valve is actuated in one direction, it will supply pressure to the plungers of the cylinders 36, and as the valve is moved in the opposite direction it will open the exhaust passages to permit return movement of the plungers 35 under action of a reverse pressure, with suitable exhaust of the inert fluid.

In a similar manner, a controlling valve 24^a controls pressure through supply pipe 40^a, and branch pipes 41^a, to the opposite ends of cylinders 36, to reverse the movement of plungers 35 to release the wedges 32, after each sectional bending of the flange.

For the purpose of thus actuating each valve 24 and 24^a, their stems 43 are each provided with a double ended lever 44, extending at one side into the range of a pin or abutment 45, suitably located on gear *b*, as on one of the arms thereof, and extending at the other side in the range of a similar pin or abutment 46, also properly located and timed, as will be observed from Figs. 4 and 5.

In operation, pin 45, in the normal movement of the gear, will engage the outer arm of lever 44, wiping past it, and opening pressure to cylinders 36, and after such pressure has been exerted a sufficient length of time, as during the bending of the flange, abutment 46 will then come into contact with the opposite arm of the lever, depressing it and opening the valve to exhaust, permitting retraction of the wedges 32.

In the same manner, abutment 46 likewise operates the other arm 44 to actuate valve 24 to reverse plungers 35 to release wedges 32 at the end of the pressing period, it being understood that the location of the abutments 45—46 on the gear *b*, the positioning of the arms 44, and the timing of the valves is properly proportioned to effect the movements as desired in proper sequence, as will be readily understood.

In order to provide clearance for removal of the flanged plate, the pressure bracket 31 is adjustably mounted on a suitable supporting frame 47 secured to the front of head 4, as shown. Bracket 31 is pivoted by

bolts 48 at each side so as to swing upwardly and outwardly, with its clamping mechanism, to allow of removal of the flanged plate, as indicated in dotted lines, Fig. 1.

- 5 A dowel pin or bolt 49 at each side serves to hold the bracket 31 fixedly in lowered or raised position by engagement in either of the holes 50, as will be readily understood. The terminal connections 41 for the pressure 10 pipes are made flexible, as by sections of rubber hose, allowing for the necessary movement of the cylinders with the bracket.

As thus arranged, the mechanism is capable of continuous and semi-automatic operation, in so far as the clamping and bending steps are involved, it being only necessary to move the plate *e* upon its pivotal mounting sufficiently far for the next bending operation. It will be understood that, in mechanism of this kind, there are preferably carried out a plurality of complete annular manipulations and bending operations, so that variations in the desired circular contour of the flanged plate are compensated for and smoothed out by continuing the series of annularly progressive bending movements during two, three, or more complete annular series.

The construction and operation of the invention will be readily understood and appreciated from the foregoing description. The several parts are comparatively few and simple, of cheap construction, and may, of course, be made of the proper size, degree of angle, or otherwise modified by the skilled mechanic, to adapt the machine to the work in view. All such changes are to be understood as within the scope of the following claims.

40 What I claim is:

1. In combination with a supporting base and a reciprocable power driven head, a bracket mounted on the base provided with an L-shaped anvil block having an inwardly and downwardly sloping rear face and a forwardly extending supporting face, and a co-acting pressing die secured to the reciprocable head and provided with a correspondingly inclined face adapted to bend 45 a flange against the rear face of the anvil block.

2. In combination with a supporting base and a reciprocable power driven head, a bracket mounted on the base provided with an L-shaped anvil block having an inwardly and downwardly sloping face, a co-acting pressing die secured to the reciprocable head and provided with a correspondingly inclined face, and a lower inclined face merging therewith by a rounded corner and at an obtuse angle to the first named face, and adapted to make first bending contact against the edge portion of a blank laid across the L-shaped block.

60 65 3. The combination with a supporting

base and a reciprocable power driven head, a bracket mounted on the base provided with an L-shaped anvil block having a downwardly and inwardly sloping rear face at right angles thereto, and a co-acting pressing die having a bending face inclined in parallelism with the rear face of said anvil block, adapted to bend a sheet or plate metal blank flatwise over the corner of the L-shaped anvil block and against its rear face.

4. In a machine of the kind disclosed, a lower bracket provided with an anvil block having a downwardly and outwardly sloping upper face, a downwardly and inwardly sloping rear face at right angles thereto, a co-acting pressing die and means for actuating it, a forwardly extending frame provided with an adjustable threaded bracket, 80 a threaded stud extending therethrough provided with tightening devices, and a terminal reduced extension thereof providing a pivotal bearing for a blank.

5. In a machine of the kind disclosed, a lower bracket provided with an anvil block having a downwardly and outwardly sloping upper face, a downwardly and inwardly sloping rear face at right angles thereto, a co-acting pressing die and means for actuating it, a forwardly extending frame provided with an adjustable threaded bracket, 90 a threaded stud extending therethrough provided with a tightening device, and a terminal reduced extension thereof providing a pivotal bearing for a blank, said bearing and its parts being adjustable toward and from the anvil member on a plane parallel with its upper face.

6. In combination with a pressing machine of the kind disclosed provided with an anvil member, clamping mechanism comprising a plurality of wedge actuated shoes, a supporting frame therefor, co-acting wedges, fluid actuated mechanism therefor, and means for controlling said mechanism in conformity with the operation of the machine.

7. Clamping mechanism for a blank in a pressing machine of the kind disclosed comprising a supporting frame, a plurality of pressing shoes having actuating stems, wedges therefor provided with reciprocable bars, fluid actuated plungers connected therewith, cylinders therefor, controlling valves for said cylinders, and means actuated by a portion of the pressing machine for actuating said valves to apply or release pressure.

8. Pressing mechanism for a blank in a machine of the kind disclosed comprising a supporting frame, a plurality of pressing shoes each provided with a pressure stem and spring-controlled retracting stems, wedge mechanism for the pressing stems,

fluid pressure mechanism for actuating said wedges, and means dependent on the operation of the machine for controlling the fluid pressure supply of said mechanism.

9. Pressing mechanism for a blank in a machine of the kind disclosed comprising a supporting frame, a plurality of pressing shoes each provided with a pressure stem and a spring-controlled retracting stems, wedge mechanism for the pressing stems, fluid pressure mechanism for actuating said wedges, controlling valves and pressure applying connections between the valves and said mechanism, abutments located on a moving part of the machine, and actuating means for the valves arranged in the path of said abutments.

10. In combination with the gearing of a pressing machine having a reciprocable head, pressure actuating mechanism provided with operating cylinders, pressure controlling valves therefor having tilting arms,

and a plurality of abutments on the gearing adapted to engage said arms, said parts being mounted on and carried by the reciprocable head.

11. In a pressing machine having a reciprocable head, a bracket pivoted on the head provided with pressure applying mechanism adapted to act on a blank, and means for locating the bracket in lowered operative position or raised inoperative position.

12. In a pressing machine having a reciprocable head, a bracket pivoted on the head provided with pressure applying mechanism adapted to act on a blank, and removable locking devices for holding the bracket on the reciprocable head in a lowered operative position and in a raised inoperative position respectively.

In testimony whereof I hereunto affix my signature.

JOHN HUBER.
